CONCEALED RADIATION HEAT EXCHANGER

Application filed April 3, 1931. Serial No. 527,567.

The present invention relates generally to a heat exchange apparatus and more particularly to a concealed wall heater or enclosed cabinet heater so situated as to induce a circulation of air at a low level and return it to a higher level at a different temperature.

Heating devices of the type to which this invention relates have heretofore been characterized by a coil or other heating element concealed in a duct, the upper and lower ends of which communicate with a room at two levels. In such constructions the heating element of necessity has been placed above the inlet for the air and the air is therefore drawn into the lower vacant chamber of the duct to there rise vertically to and through the heating element. This arrangement has been found in practice to have many disadvantages among which capacity limitation

plays an important part. Thus the capacity of a given length and height of enclosure and for a given surface is limited by the depth of the duct or enclosure as a controlling factor on amount of surface that can be efficiently used. Beyond this limit a capacity increase can only be obtained by providing additional heating surface above the original surface or coil. The superposing of one surface upon another results in increased resistance which reduces the expected gain in heating. The height of the stack plays an important part in these vertically superposed surfaces in that a high stack will show considerably better percentage gain than a low stack under like conditions, though neither give a capacity increase even approaching the percentage increase in heating surface. Furthermore, with a heating surface of finned construction placed in a duct above the air inlet the design must be such that the heating element fits snugly in the duct, otherwise open spaces are formed between the outer surface of the element and the inner wall of the duct to cause by-pass losses. To do this adds materially to the expense of installation because a complete enclosing smooth metal duct must be employed about the heating element to overcome irregularities of brick, plaster, and other construction material. Another feature of previous heating devices of the type

to which this invention relates is the location of a throttling damper in the upper portion of the duct, at the lower end of which is located the heating element. The purpose of this damper is to throttle the amount of air passing through the unit and thus reduce its heating capacity. This device has given rise to many disadvantages, in that as it decreases the flow of air the resulting air stream is at a much higher temperature, which rises more rapidly toward the ceiling thus giving much less efficiency and less effective heating. Also, when the damper is entirely closed due to its location at the top of the duct, this entire duct becomes filled with very high temperature air, with a resulting loss of heat either through the outer wall where it is wasted or through the inner wall to the room into which it is desired to decrease the heat emission.

Some of the objects of the present invention are to provide an improved unit for concealed radiation purposes; to provide a heat exchanger so arranged and associated with other parts as to ensure complete and intimate contact of all entering air with such exchanger; to provide a concealed type of heat exchanger wherein operating losses are reduced to a minimum; to provide a heat exchanger for concealed radiation wherein an increase in the capacity of the unit can be made more efficiently and more economically than heretofore; to provide a concealed heat exchanger wherein a given volume of air passing therethrough meets with minimum resistance and gives a greatly increased volume of circulated air as compared to prior radiation systems; to provide a heat exchanger mounted in a vertical position and in such relation to the air inlet that incoming air traverses such exchanger substantially horizontally; to provide a heat exchanger whereby the greatest heating capacity can be obtained for a given space available; to provide a concealed radiation system capable of great flexibility of control without introducing loss factors when changing from one capacity to another; to provide an improved damper and by-pass control for concealed heat exchangers; to provide a grille in such form as to properly direct the induced air

while providing concealment with minimum air resistance and so associated with a heat exchanger as to increase the range of modulating control; and to provide other improvements as will hereinafter appear.

In the accompanying drawings Fig. 1 represents an elevation of a concealed radiator installation embodying one form of the present invention; Fig. 2 represents an elevation 10 on an enlarged scale and partly broken away of the inlet portion of the installation; Fig. 3 represents a sectional elevation of the complete unit on the same scale as Fig. 2, Fig. 4 represents an elevation partly broken away 15 of a modified form of heat exchanger; and Fig. 5 represents a section on line 5—5 of Fig. 4.

Referring to the drawings one form of the present invention consists of a duct 10 communicating at opposite end portions with an air inlet 11 and an air outlet 12 which are in communication with a room to be heated. The circulation of air is inward through the inlet 11, at the lower end of the duct 10, upwardly in the duct 10, and outwardly 20 through the outlet 12 passing in the meantime through a heater 13 whereby the temperature of the air is raised during its travel from the inlet 11 to the outlet 12.

30 The duct 10 can be formed by any suitable bounding walls but in the preferred construction it is defined by a casing 14 which, with the heater 13 and other associated parts, forms a complete unit for installation in the wall of the room where it may be plastered or otherwise concealed therein except for the room communicating inlet 11 and outlet 12. In some instances and more particularly in the case of external 35 cabinet units the front face of the casing 14 may be exposed to view but generally for appearance sake the casing 14 is of the construction shown in Fig. 3. This casing 14 is of generally rectangular shape and elongated horizontally rather than vertically while its depth is relatively shallow; As compared to the height of the room in which it is located the casing 14 is of dwarf dimension 40 in order to bring the outlet 12 in relatively close proximity to the floor of the room while the inlet 11 is substantially at the same level as the floor. The result desired is the removal of the cold or cooler air at the floor level and its delivery at a higher temperature 45 to the room at a level to maintain the occupied portion of the room at a mean liveable temperature with a minimum loss of heat to the ceiling portion of the room.

50 The heater 13 consists in the present instance of a plurality of pipe coils 15 arranged preferably in vertical spaced relation and receiving a heating medium, such as steam, from a header 16 which has an inlet 17 connected to the source of heat. The coils 15 are conductively bonded to a plurality of fins 18

which are mounted transversely of the coils and extend substantially the length thereof in relatively close spaced parallel relation in order to provide a plurality of air passages 20 of restricted width.

In order to obtain the new results produced by the present invention the heater 13 is supported at each end on brackets 19 extending to the rear of the casing 14 and resting upon the bottom of the casing 14 so that the assembled relation is such that the heater 13 is opposite to and in register with inlet 11 while the series of fins 18 are substantially normal to the plane of the inlet 11. Supporting members 21 can be placed at intervals 70 throughout the length of the unit to rest upon the bottom of the casing 14 as will be understood. Preferably the plane of the front edges of the fins 18 is relatively close to the plane of the inlet 11 while the plane of the rear edges of the fins 18 is spaced from the rear wall 22 of the casing 14 to provide a vertically disposed passage 23 communicating at its upper end with the duct 10; at its lower end with a by-pass passage 24 below the heater 13; and at its front with the fin passages 20. Since the top of the heater 13 is practically coincident with the horizontal plane passing through the top of the inlet 11, it is evident that the major portion of the entering air is directed horizontally through the heater 13 and rises into the duct 10 from the rear passage 23.

55 For varying the temperature and quantity of air and controlling its passage through the heater 13, a damper 25 is pivotally mounted at 26 to the rear of the heater and extends throughout the length thereof while its width is such as to project over the top of the heater 13 to meet a stop plate 27. This plate 27 is fixed to the front plate of the casing 14 and when engaged by the damper 25 cuts off all air flow through the heater so that any residual flow is diverted to the by-pass passage 24 and passage 23. A leader screw 28 is rotatably mounted in the front and rear walls of the casing 14 extending horizontally across the duct 10 and having threaded engagement with the damper 25. The thread of the screw 28 is a long pitch spiral to give a quick feed motion to the damper so that it can be shifted readily from one position to another. Preferably one end of the screw 28 extends through the front of the casing 14 to terminate in a hand knob 30 for manual control thereof. When the damper 25 is in the full line position of Fig. 3 the by-pass passage 24 is entirely shut off from the duct 10 and all entering air passes through the heater 13 to the duct 10. When the damper 25 is in the dotted line position of Fig. 3 all air from the heater 13 is cut off from the duct 10 and air entering the casing 14 is by-passed through the passages 23 and 24 to the duct 10. Any intermediate position of the damper 25

results in a mixing of cold and heated air to meet conditions which require tempering of the heated air.

As the rising air in the duct 10 nears the outlet 12 it preferably meets a baffle or deflector 31 which is so shaped and positioned as to direct the flow smoothly to the outlet. This is accomplished by giving the baffle a convex air engaging face, the curvature of which is such as to give the desired result. The outlet 12 is preferably concealed by a suitable grille 32 ornamental or otherwise in order to give the desirable finish effect without restricting the free flow of heated air.

The inlet 11 is also provided with a grille 33 but of a new form so devised as to coact in certain particulars with the heat exchanger and damper assembly to give a result not heretofore possible in prior devices. Thus in the preferred form the grille 33 is made up of a plurality of superposed blades 34 extending substantially parallel and horizontally across the inlet 11. Each of these blades 34 is curved inwardly and upwardly to lie in the space between the inlet 11 and the plane of the front of the heater 13 but are so spaced vertically with respect to each other that the lower edge of each when viewed from above the inlet appears to meet the top edge of the next lower blade and so prevents anyone from seeing through the intervening space. In other words the arrangement of the blades 34 is such that the heater parts are entirely concealed from the view of anyone in the room

but allow free ingress of air. Thus while serving the purpose of concealment the grille 33 gives the maximum free entrance area with the result of minimum resistance and maximum radiator capacity. Furthermore a coactive relation exists between the damper 25 and the grille 33 in that a closing of the damper 25 decreases the capacity of the heater to a minimum while the blades 34 act to reduce to a minimum direct radiation to the room and also to decrease the circulation of air which might enter through the lower portion of inlet 11, pass over part of heater 13 and leave through upper portion of inlet 11. By the blade construction of the grille of the present invention the oblique blades help to trap or pocket the air directly in the heater and so block upward flow of air when the damper is closed.

In the form of the invention shown in Figs. 4 and 5 a modified type of heat exchanger is employed, but for convenience in following the drawings those parts which have been described and are common to Figs. 1 to 3 inclusive have been identified by like reference numerals. In this form the exchanger is made up of transversely arranged pipes 35, but these are of the finned tube type and therefore each is provided with its own set of fins 36 arranged in closely spaced relation throughout the length thereof to form the

desired passages through which the air can circulate. This unit is located in register with the inlet to the duct so that the entering air passes transversely across the pipes 35 between the fins and then rises vertically in the passage 23 to enter the duct 10 and be discharged at a different level and different temperature to a room. The inlet in this instance, as in the form of the invention already described, is provided with a grille 36, the louvers 37 of which are respectively of arcuate form and inwardly disposed to partially encircle the top portion of each finned tube. This results in the formation of a plurality of superposed passages 38 which direct different streams of air over the individual pipes.

From the foregoing it will be seen that a heating device has been devised which is characterized by two openings into a room which are spaced by a solid wall forming with other walls an enclosed duct in communication with the two openings. This duct terminates at its lower end in the approximate plane of the top of the lower opening but has communication with the heater which is located below the aforesaid plane. This construction gives a result not heretofore attained by any wall type of heater or so-called base board heater in that the entering air passes horizontally through the heater whereby capacity and air flow are increased for a given depth of recess, better efficiency obtained, less air friction created, greater uniformity of temperature secured, heat loss to surrounding walls reduced due to greater air volume at lower temperature. These advantageous results accrue primarily by reason of the new relation between the heat exchanger and the inlet in that both vary as to size for changes of capacity without change in length, height or depth of recess, but always the exchanger remains in registering alignment with the aforesaid inlet. In the construction here shown by way of example an inlet is provided of a size to coact with an exchanger made up of four conduits, but for conditions requiring less capacity three, two, one or any other number of conduits may be employed, each, however, with its particular size duct inlet and each in assembled condition being subjected to the full substantially horizontal air flow from its inlet. Thus capacity of a given height and length of enclosure is not limited by the depth of enclosure and any variation of these factors gives more efficient heating throughout the entire range. For example by doubling the surface of the heat exchanger from two conduits to four conduits and similarly increasing the area of the inlet, the free area admitting air to the duct is doubled. Hence a given volume of air passing through the exchanger meets with less resistance resulting in a marked increase in the volume of air being circulated and also by delivering air

at a lower temperature gives a better heating effect.

Similarly, it has been found that by maintaining the same cabinet dimensions as to length, height, and depth, the same surface, if spread over a larger vertical front opening, which increases the free area of opening and decreases the length of air travel, will give a material increase in capacity. Such arrangement of surface has not been possible in the existing devices in this field; for in the past it has been necessary to increase either depth, length, or height of recess to obtain a capacity increase with any reasonable degree of efficiency. With the construction described in this invention and utilizing the same type of heating surface, it is always possible to obtain the greater capacity for a given depth of recess than with the previously accepted type with vertical air flow through the heating surface.

While the capacity of a given recess has been greatly increased by the distinctive features of the foregoing device, its efficiency and heating economy have been still further improved by means of the functions performed by the by-pass damper. When a modulation of the heat output of this unit is desired and the by-pass damper is moved part way from its position permitting no by-passed air, to its position permitting full by-pass of air, there results two streams of air passing up through the air duct. The volume of air passing through the coil has been reduced with a consequent increase in temperature. In previous heating devices of this type this decreased volume of higher temperature air has been permitted to enter the room being heated, with the result that it rises rapidly to the ceiling, overheating that zone. In this invention this reduced volume of higher temperature air is mixed with a substantial quantity of cold air which has entered the stack through the by-pass. This increases the total volume of air leaving the duct and decreases its temperature, resulting in a decreased tendency to rise and a much improved heating effect throughout the room. Thus, as the damper is brought over to close off the heating coil, the temperature of the air leaving the unit is continually reduced without as marked a reduction in volume, whereas with previous devices the reduction in heating capacity has been accompanied by a decrease to substantially zero in the volume of air together with a marked increase in air temperature.

Having thus described my invention, I claim:

1. A heat exchanger assembly comprising a plurality of walls forming a duct having an inlet and an outlet, a heat exchanger located in horizontal alignment with said inlet and providing a plurality of passages for air to travel into said duct, and louvres for direct-

ing incoming air substantially horizontally through the interchanger.

2. A heat exchanger assembly comprising a plurality of walls forming a duct having an inlet and an outlet, a heat exchanger located in horizontal alignment with said inlet and providing a plurality of passages for air to travel into said duct, louvres for routing air to the interchanger, and means forming a by-pass passage between said inlet and outlet and around said exchanger. 75

3. A heat exchanger assembly comprising a plurality of walls forming a duct having an inlet and an outlet, a heat exchanger located in horizontal alignment with said inlet and providing a plurality of passages for air to travel into said duct, louvres for routing air to the interchanger, means forming a by-pass passage between said inlet and outlet and around said exchanger, and a damper for 80 controlling said by-pass passage. 85

4. A heat exchanger assembly comprising a plurality of walls forming a duct having an inlet at one end portion and an outlet at the other end portion, a heat exchanger consisting of a conduit of conducting material and a plurality of fins bonded to said conduit to form a series of air passages transverse of said conduit, and means for mounting said exchanger in said duct whereby the vertically 90 disposed inlets to the respective fin passages are all horizontally opposite said duct inlet. 95

5. A heat exchanger assembly comprising a plurality of walls forming a duct having an inlet at one end portion and an outlet at the other end portion, a heat exchanger consisting of a conduit of conducting material and a plurality of fins bonded to said conduit to form a series of air passages transverse of said conduit, means to mount said exchanger with the fins spaced from the bottom of said duct to form a by-pass passage and with the vertically disposed inlets to the respective fin passages horizontally opposite said duct inlet, and a damper for controlling said by-pass passage. 100 105

6. A heat exchanger assembly comprising a plurality of walls forming a duct having an inlet and an outlet vertically spaced apart, means forming a by-pass passage between said inlet and outlet and around a heat exchanger located in horizontal alignment with said inlet and providing a plurality of passages for air to travel into said duct. 110 115

7. A heat exchanger assembly comprising a plurality of walls forming a duct having an inlet and an outlet, a heat exchanger mounted in horizontal alignment with said inlet and providing a plurality of passages for air to travel into said duct, and a grille mounted in said inlet having a plurality of superposed blades for admitting air while concealing said exchanger. 120 125

8. A heat exchanger assembly comprising

a plurality of walls forming a duct having an inlet and an outlet, a heat exchanger mounted in horizontal alignment with said inlet and providing a plurality of passages for air to travel into said duct, a damper for closing the outlet side of exchanger, and a grille in said duct inlet provided with blades arranged one above another and inwardly inclined to decrease extraneous air flow when

5 said damper is closed.

10 9. A heat exchanger assembly comprising a plurality of walls forming a concealed duct having an exposed inlet and an exposed outlet vertically spaced apart, and a heat exchanger located in register with said inlet to intercept air passing substantially horizontally through the exchanger to said duct.

15 10. A heat exchanger assembly comprising a plurality of walls forming a duct having an inlet and an outlet, a heat exchanger located in register with said inlet and spaced from the rear wall of said duct and from the bottom thereof, and a damper mounted to swing toward said exchanger and fit about the rear portion thereof to cut off all flow of air through said exchanger to said duct but allowing air to travel beneath said exchanger

20 into said duct.

25

30 11. A heat exchanger assembly comprising a plurality of walls forming a duct having an inlet and an outlet, a heat exchanger located in register with said inlet and spaced from the rear wall of said duct and from the bottom thereof, and a damper so mounted as

35 to control both air passing through said exchanger and around said exchanger whereby the air leaving said outlet can be tempered in a predetermined manner.

40 12. A heat exchanger assembly comprising a plurality of walls forming a duct having an inlet and an outlet, a heat exchanger in register with said inlet formed of pipes having individual fins thereon, said pipes being arranged in superposed relation, and louvers

45 or blades mounted to respectively direct air from said inlet across said finned pipes substantially in a horizontal direction.

50 In testimony whereof I affix my signature.
CARLYLE M. ASHLEY.
